(57) **CLAIM**

The ornamental design for a stand for projector, as shown and described.

DESCRIPTION

FIG. 1 is a front, right side, perspective view of a stand for projector showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view with the projector thereof;

FIG. 9 is a front, right side, perspective view in a rotated state of ballhead with the projector thereof; and,

FIG. 10 is a front, right side, perspective view in a folded state thereof.

The broken lines indicate unclaimed portion of the article that form no part of the claimed design.
